UNITED STATES PATENT OFFICE.

JOSEPH BROADHEAD, OF CORNWALL, NEW YORK.

BLANKET.

SPECIFICATION forming part of Letters Patent No. 312,323, dated February 17, 1885.

Application filed November 24, 1884. (Specimens.)

To all whom it may concern:

Be it known that I, JOSEPH BROADHEAD, of Cornwall, in the county of Orange and State of New York, have invented an Improvement 5 in Blankets, of which the following is a specification.

Before my invention, fabrics had been made of a foundation of cotton or hemp, woven plain, and a layer of wool upon one or both 10 sides fitted through such foundation, and then the wool surface has been printed in figures or designs. My invention, therefore, does not relate to either of the foregoing features, nor to the machine for felting the 15 wool and jute together, as a machine adapted for this object is shown in Letters Patent No. 123,136, granted January 30, 1872, to Milton D. Whipple.

In the manufacture of horse-blankets it is 20 usual to employ a foundation of jute or similar material with a lining of woven fabric—such as wool or wool and cotton mixed. The two sheets of fabric have to be cut out, laid together, and bound. This entails considerable 25 labor, and neither fabric supports the other; consequently the lining is very soon worn or torn, and the blanket becomes useless. In addition to this, it is found that with the ordinary lined blanket the perspiration 30 is liable to condense and the blanket to become wet. This is injurious to the animal, and the blanket is quickly destroyed.

My improvement is made with reference to the manufacture of horse-blankets that are 35 softer and more flexible than those heretofore made, and are stronger and of a single thickness, and both surfaces have a fleecy appearance from the wool employed, and the exterior surface is in various colors to obtain the 40 proper appearance, and the lining is of wool, so as to afford the necessary warmth, and not to injure the hair of the animal. The perspiration is allowed to pass off freely through the pores of the blanket, and the blanket does 45 not become wet, and it is as useful in this respect as the expensive all-wool blankets.

In carrying out my invention, I weave a foundation of jute of the necessary strength and thickness in two or more colors, usually 50 in plaids or checks. I then lay upon one of

the surfaces a sheet of wool-batting, either colored or white, and I pass the same through a felting-machine—such, for instance, as that in the aforesaid patent—and in so doing the wool is carried into and through the jute foundation sufficiently to firmly secure the wool to the foundation, and at the same time to draw or force sufficient of the wool through the fabric to give the surface a fleecy appearance or nap. The jute foundation, which ordinarily 55 is harsh and stiff, is rendered comparatively soft and pliable by the penetrating needles opening the threads and carrying in wool, which felts into the fabric, and the color of the jute, which ordinarily is harsh and objectionable, is subdued and softened by the wool projecting through it, and giving to the fabric a finished appearance, and the strength of the blanket is increased by the felting action and the presence of the wool in the fabric. The exterior of the horse-blanket is by 60 this mode of manufacture in checks, stripes, or mottled colors derived from the different colors of warp and weft used in weaving the jute foundation, and the inner surface, being of 65 wool, is of the proper warmth for the animal, and the wool forms a protection to the animal's hair from the jute, which ordinarily is 70 too harsh to be next the skin.

In the drawings, Figure 1 represents a horse-blanket, and in the section, Fig. 2, the woven jute foundation is shown at *a*, and the inner layer of wool at *b*, and the exterior surface at *c*.

The edges may be bound as at *d*.

This horse-blanket made as aforesaid is a 85 new article of manufacture.

I claim as my invention—

The blanket having a woven jute foundation of different colors, and a back of wool felted into the jute foundation, the wool showing upon the face and mingling with the colors of the jute to form the outside or face of such blanket, substantially as set forth.

Signed by me this 20th day of November, A. D. 1884.

JOSEPH BROADHEAD.
